CLAIM

The ornamental design for a capping system for use with one or more medical connectors, as shown and described.

DESCRIPTION

FIG. 1 is a perspective view of an embodiment of a capping system for use with one or more medical connectors; FIG. 2 is a top plan view thereof, wherein a bottom plan view thereof is identical to that shown in FIG. 2; FIG. 3 is a right side elevation view thereof, wherein a left side elevation view thereof is identical to that shown in FIG. 3; and, FIG. 4 is a rear elevation view thereof, wherein a front elevation view thereof is identical to that shown in FIG. 4. The broken lines immediately adjacent the shaded areas represent the bounds of the claimed design, while all other broken lines are directed to environment and are for illustrative purposes only; the broken lines form no part of the claimed design.
